(57) **CLAIM**

The ornamental design for apparatus for supply of gas as shown and described.

DESCRIPTION

1. Apparatus for supply of gas

FIG. 1.1 is a front view of an apparatus for supply of gas showing the new design;

FIG. 1.2 is a back view thereof;

FIG. 1.3 is a top view thereof;

FIG. 1.4 is a bottom side view thereof;

FIG. 1.5 is a right side view thereof;

FIG. 1.6 is a bottom view thereof;

FIG. 1.7 is a top perspective view thereof; and,

FIG. 1.8 is a bottom perspective view thereof.

The characteristic features of the design lie in the shape of the apparatus for supply of gas as shown.

1 Claim, 8 Drawing Sheets
